William & Patchek

UNITED STATES PATENT OFFICE.

CHARLES W. HUTCHINSON, OF NEW ROCHELLE, NEW YORK.

CURTAIN HANGER.

1,409,722.

Specification of Letters Patent. Patented Mar. 14, 1922.

Application filed June 28, 1921. Serial No. 481,000.

To all whom it may concern:

Be it known that I, CHARLES W. HUTCHINSON, a citizen of the United States, and a resident of New Rochelle, county of Westchester, State of New York, have invented certain new and useful Improvements in Curtain Hangers, of which the following is a specification.

This invention relates to curtain fixtures and has particular reference to brackets or supports adapted to be used in connection with curtain rolls employing the conventional form of spring mechanism for winding the curtain thereupon.

An important object of the invention is to provide in a device of the above mentioned character a means whereby the winding pintle of the spring mechanism may be positively locked against rotation while the curtain roll is being actuated against the spring mechanism, and of such a nature as to permit the pintle to be readily unlocked in order that the spring mechanism employed may be adjusted to a desired tension without necessitating the removal of the curtain roll from its supports.

Another object is to provide a device of the character mentioned which is simple in construction, inexpensive to manufacture and reliable in operation.

Other objects of my invention will become apparent from the following description taken in connection with the accompanying drawings, in which—

Figure 1 is a fragmental elevation of a curtain roll, the pintle of which is supported or retained by the device embodying my invention.

Figure 2 is a sectional view taken on line 2—2 of Figure 1.

Figure 3 is a sectional view taken on line 3—3 of Figure 2.

Figure 4 is a fragmental elevation of a curtain roll, the pintle of which is supported or retained in position by a modified form of device embodying my invention.

Figure 5 is a sectional view taken on line 5—5 of Figure 4.

Figure 6 is a sectional view taken on line 6—6 of Figure 4; and

Figure 7 is a sectional view taken on line 7—7 of Figure 5.

In the drawings, attention being called to Figures 1 to 3, inclusive, wherein is shown the preferred form of my invention, the numeral 5 indicates a window frame with which

the conventional type of curtain roll 6 is associated, the curtain roll 6 being provided with a curtain 7 adapted to be rolled upon or unrolled from the curtain roller 6. The end of the curtain roll 6, not shown in the drawings, is adapted to be rotatably mounted upon or connected to the window frame 5 by any of the well known types of brackets employed for supporting curtain rolls, but the opposite end, which is provided with the ordinary pintle 8 having the usual connection with the spring mechanism, not shown, for operating the curtain roll, is supported by the bracket or fixture embodying my invention and indicated as a whole by the numeral 9. The fixture 9 comprises a base plate 10 adapted to be attached to the window frame 5 by means of nails or screws as shown at 11, the base plate 10 being provided with a boss or flange 12 having a central bore 13 and cut away as shown in Figures 1 and 2 to provide an entrance slot 14. It will be noted that the central bore 13 of the boss 12 is so formed as to provide a cam-faced surface 14' and an abutment 15, the function of both of which will be hereinafter referred to. Within the boss 12 there is disposed a rotatable pintle-receiving element 16, one end of which is provided with a flange 17 adapted to be seated upon the bearing surface 18 at the jointure of the base 10 with the boss 12. The rotatable pintle-receiving element 16 is provided therein with a slot 19 adapted to register with the opening 14 in order that the pintle 8 may be inserted into the pintle-receiving element 16 or readily removed therefrom.

In the event that it becomes necessary to adjust the spring mechanism, not shown, of the roller 6 to a desired tension, it is unnecessary to remove the pintle 8 from the pintle-receiving element 16, inasmuch as the adjustment may be accomplished by unrolling the curtain 7 from the curtain roll 6 against the tension of the spring mechanism, not shown, after which the curtain roll 6 is rotated in an opposite direction by hand to roll the curtain 7 upon the same. By reason of the fact that the pintle 8 normally resting upon the cam face 14' and in contact with the abutment 15, it is apparent that the same is held against rotation when the curtain 7 is being unrolled from the curtain roll 6 against the tension of the spring mechanism thereof not shown; but it is also apparent that by reason of the inclination of the cam surface

- 14', the pinte 8 will be lifted or elevated into the pinte-receiving groove 19 when the curtain roll 6 is rotated in an opposite direction, the pinte 8 being held against rotative movement with respect to the roller 6 by the usual form of pawl and ratchet mechanism not shown. After having rolled the curtain 7 upon the curtain roll 6 by hand as above described, the pinte 8 will drop by gravity to the position shown in Figure 2, when the curtain 7 is again unrolled from the curtain roll 6 against the tension of the spring mechanism, in which position the pinte is locked against rotation when the curtain 7 is being unrolled from the curtain roll 6 against the tension of the spring mechanism. By repeating the above described operations it is obvious that the tension of the spring mechanism not shown of the curtain roll 6 may be adjusted to any desired strength without necessitating the removal of the pinte 8 from the pinte-receiving element 16.
- Attention being directed now to Figures 4 to 7, inclusive, wherein is shown a modified form of my device, it will be noted that the device indicated as a whole by the numeral 20 comprises a base 21 adapted to be secured to the window frame 5 by means of screws or nails 11 in the manner hereinbefore mentioned in connection with the form of my device indicated by the numeral 9, and that the base 21 is struck up to form a yoke 22, provided with a boss 23 which is cut away as shown in Figure 5 to form an entrance slot 23' and provided with a central bore 24 adapted to receive a rotatable pinte-receiving element 25 having a slot 26 formed therein adapted to register with the slot 23' in order to permit the insertion of the pinte 8. The pinte-receiving element 25 is provided with a sprocket 27 which as shown in Figure 4 is positioned intermediate the yoke 22 and the window frame 5. Over the sprocket 27 there is passed a chain 28 by means of which the sprocket 27 together with the pinte-receiving element 25 is rotated in the direction indicated by the arrow shown in Figures 5 and 6, in order that the spring mechanism, not shown, of the curtain roll 6 may be adjusted to any desired tension, as will hereinafter more clearly appear. In order to prevent the pinte-receiving element 25 from rotating with the curtain roll 6 when the curtain 7 is being unrolled from the curtain roll 6 against the tension of the spring, not shown, I provide a plunger 29 which is disposed within a passage 30 formed within the pinte-receiving element 25, the plunger 29 being adapted to reciprocate within the passage 30 and engage an abutment 31 adjacent the cam face 32. It is obvious that by the construction which I employ the pinte-receiving element 25 may be rotated in the direction indicated by the arrow in Figures 5 and 6, but that its rotation is prevented in

the opposite direction when the curtain is being unrolled from the curtain roll 6 against the tension of the spring mechanism not shown.

To adjust the tension of the spring mechanism, not shown, of the curtain roll 6 to a desired degree, by the modified form of my device the curtain roll 6 is prevented from rotating by holding the curtain 7, whereupon the pinte-receiving member 25 is rotated in the direction indicated by the arrows shown in Figures 5 and 6 through the instrumentality of the sprocket 27 and its associated sprocket chain 28, until the desired tension is reached.

While I have shown and described what I at present consider the preferred embodiments of my invention, it is to be understood that I do not wish to limit myself to the specific construction shown, and that various changes may be made in the size, shape and arrangement of parts without departing from the spirit of the invention or the scope of the subjoined claims.

Having thus described my invention, I claim:

1. A curtain fixture comprising an attachment plate, a boss carried by said plate, said boss being provided with an entrance slot and a bore, a rotatable pinte-receiving element journaled within said boss, said pinte-receiving element being provided with a pinte-receiving slot adapted to register with said entrance slot to permit the insertion of the curtain pinte, and means for locking said pinte-receiving element against rotation.

2. A curtain fixture comprising an attachment plate, a boss carried by said plate and provided with an entrance slot, a pinte-receiving element having a pinte-receiving slot formed therein, said pinte-receiving element being journaled within said boss and adapted to be moved to bring the pinte-receiving slot into registration with said entrance slot to permit the insertion of the curtain pinte and further adapted to be moved to sever communication between the entrance slot and the pinte-receiving slot, whereby the pinte is locked within the pinte-receiving slot, and means for locking said pinte-receiving element against rotation in one direction and adapted to permit rotation thereof in an opposite direction.

3. A curtain fixture adapted to be used to support the pinte end of a spring actuated curtain roll comprising an attachment plate, a boss associated with said plate, a rotatable pinte-receiving element journaled within said boss and having a pinte-receiving slot formed therein, and means associated with said boss and adapted to be engaged by the pinte whereby the pinte-receiving element is locked against rotation.

4. A curtain fixture adapted to be used to support the pinte end of a spring actuated

curtain roll comprising an attachment plate, a boss associated with said plate, a rotatable pintle-receiving element journaled within said boss and having a pintle-receiving slot formed therein, means associated with said boss and adapted to be engaged by the pintle whereby the pintle-receiving element is locked against rotation in one direction, and means for relieving engagement between the pintle and the first mentioned means when the pintle-receiving element is rotated in an opposite direction.

5. A curtain fixture adapted to be used to support the pintle end of a spring actuated curtain roll comprising an attachment plate, a boss carried by said attachment plate, said boss being formed with an abutment and a cam face and having a pintle-receiving slot provided therein, a pintle-receiving element 10 journaled within said boss and provided with a slot adapted to receive the pintle, the pintle being adapted to engage the abutment to lock the pintle-receiving element against rotation in one direction and adapted to be 15 lifted by the action of the cam face thereupon to permit the pintle-receiving element to be rotated in the opposite direction.

6. A curtain fixture adapted to be used to support the pintle end of a spring actuated

curtain roll comprising an attachment plate 30 provided with an abutment and having a pintle-receiving slot formed therein, the pintle being adapted to engage the abutment whereby the same is locked against rotation when the curtain roll is being actuated 35 against the tension of the spring mechanism in one direction, and means for lifting said pintle free of said abutment when the curtain and pintle are rotated in an opposite direction.

7. A curtain fixture adapted to be used to support the pintle end of a spring actuated curtain roll comprising an attachment plate provided with an abutment and having a pintle-receiving slot inserted therein 45 the pintle being adapted to engage the abutment whereby the same is locked against rotation when the curtain roll is being actuated against the tension of the spring mechanism in one direction, and means in 50 the form of a cam associated with said plate for lifting said pintle free of said abutment when the curtain and pintle are rotated in an opposite direction.

In testimony whereof, I have affixed my 55 signature to this specification.

CHARLES W. HUTCHINSON.
